UNITED STATES PATENT OFFICE.

LOUIS J. LAROCHE, OF READING, PENNSYLVANIA, ASSIGNOR TO DICK BROTHERS,
OF READING, PENNSYLVANIA, A CORPORATION OF PENNSYLVANIA.

DESIGN FOR A TREE HOLDER.

Application filed June 19, 1929. Serial No. 31,753. Term of patent 3½ years.

To all whom it may concern:

Be it known that I, LOUIS J. LAROCHE, a citizen of United States, residing at Reading, in the county of Berks and State of Pennsylvania, have invented a new, original, and ornamental Design for Tree Holders, reference being had to the accompanying drawing forming a part thereof.

The figure is a perspective view of a tree holder showing my new design.

I claim:—

The ornamental design for a tree holder, as shown.

In testimony whereof I affix my signature.

LOUIS J. LAROCHE.
